OF TENAFLY, NEW JERSEY, ASSIGNEES TO THE LAMSON COMPANY, OF BOSTON,
MASSACHUSETTS, A CORPORATION OF MASSACHUSETTS.

CENTRAL STATION FOR CARRIER-DISPATCH SYSTEMS.

Application filed August 5, 1922. Serial No. 579,884.

To all whom it may concern:

Be it known that we, FREDERICK G. WHITTIER and HAROLD S. THAYER, citizens of the United States of America, and residents 5 of Ipswich and Tenafly, in the counties of Essex and Bergen and States of Massachusetts and New Jersey, respectively, have invented new and useful Improvements in Central Stations for Carrier-Dispatch Systems, 10 of which the following is a specification.

This invention relates to central station apparatus useful in dispatch systems wherein carriers for merchandise, papers, money, 15 etc. are received at a central point from any of a series of outlying stations and from which central station such carriers, after removal, exchange or inspection of their contents, are returned to the respective sending stations. For purposes of illustration 20 the invention is herein explained as applied to the central or cashier's station of a carrier dispatch system of that type commonly employed in stores, and in which the carriers are transmitted to and from the cashier's station by means of an endless traveling cable.

The present invention secures the advantages of an improved relation of central station facilities to the number of operators and the activity of the business in a cable actuated carrier system. The patent to 25 Whittier, No. 1,365,428, January 11, 1921, explains the value of improvement of such relations in connection with a central station for pneumatic dispatch carriers, and his patent may be referred to for its discussion of the advantages of a proper relation of the activity of any such system to the central station facilities, and for its instances 30 of improved central station handling of the traffic in carrier dispatch systems of the pneumatic type. While the pneumatic system of carrier distribution is in many respects the most efficient heretofore devised, it has not as yet come into universal use. In many of the older establishments having 35 cable carrier systems installed, the proprietors are reluctant to change to a pneumatic system, the expense and trouble of making such change being regarded as a reason for retaining the reasonably satisfactory cable system. The smaller first cost and greater compactness of cable installation is often

inductive to a decision in its favor for new, 55 particularly the smaller, establishments, while in some cases mere personal idiosyncrasies on the part of proprietors have been responsible for the choice of the cable system. For these reasons the cable systems 60 occupy a valuable and permanent place in the art.

As mercantile establishments grow, the demands upon the cashier's department constantly increase, and when such department 65 is served by a cable system, the same difficulties of efficient central station service as in the case of pneumatic systems are encountered. The cable carrier system being typically, though not exclusively, employed 70 in smaller stores where saving in space and expense in installation are matters of great importance, it is desirable to provide that the central station apparatus shall be compact, and so arranged as to permit the performance of a maximum number of transactions in a given floor space. 75

The volume of business in mercantile establishments fluctuates greatly from day to day and even from hour to hour and in small establishments the business may at times become so small that a single operator should be able to care both for cash and credit transactions. It is thus desirable to provide a central station apparatus suitable 80 for use with any of the usual cash carrier systems and use by as many operators as may be necessary for heavy business, but which shall be of a character such as to permit of the delivery to and return by a single operator, if necessary, of incoming carriers of all kinds arriving from any of the various outlying stations. 85

The employment of closed carriers in a carrier dispatch system makes it necessary for the operator at the central station to grasp the carrier and manipulate some part or parts of the carriers in order to gain access to the interior. If, however, the carriers be delivered promiscuously, the operator must make a conscious effort to so grasp a carrier as to permit it to be opened quickly and without danger of spilling its contents. As the work at the central station during 90 rush periods, at least, must be performed with the utmost dispatch, efficiency demands that the movements required of the operator be reduced to a minimum, and that such 95

movements as are absolutely necessary should be of unvarying character, so that they may become substantially involuntary.

The principal objects of the present invention are accordingly to provide for efficient receipt at, handling and dispatch of carriers from the central station of a dispatch system in such a manner that each outlying station may be served with equal rapidity, and in the sequence of and arrival of carriers from any of the outlying stations at the central station; and to provide for permitting the number of operators employed to be determined in direct ratio to the volume of business transacted.

Other objects are to provide a central station apparatus for cash carrier systems of a simple, compact, durable and inexpensive type and adapted to receive incoming carriers without necessitating any manipulation of the carrier or of its parts to release it from its guide rail, track, or other conductor, and to distribute such carriers in orderly succession and in similarly oriented position within easy reach of the operator or operators, as well as to provide for the convenient return of carriers to the respective sending stations, all with a minimum amount of exertion on the part of the operator.

Specific ways of and apparatus for attaining the above objects selected for explanation of this invention provide a central station desk of elongate form having operator's stations upon one or both sides and having the incoming or delivery ends of the carrier guideways from the various outlying sending or clerk's stations, arranged in a bank at one or both ends of the desk, and preferably centrally of the width of the desk. The delivery ends of such guideways are substantially unobstructed so that carriers drop freely therefrom. As the carriers drop, they are received upon an inclined chute or a moving belt or both and are caused to move in succession, and in the order received, longitudinally of the desk and preferably along its middle, where they are readily accessible to operators seated at one or both sides of the desk. The chute or belt may have associated therewith guiding means whereby the carriers are prevented from turning during their movement along the desk and are thus always presented in predetermined position to be grasped by the operator. Such belt or chute preferably stops short of the length of the desk and may deliver the carriers, if not previously removed by the operator, into a trough forming a continuation of the guiding means, and along which they are pushed by subsequently arriving carriers. The carriers are thus presented before the operator in orderly succession and the operator is enabled to select the carriers in

accordance with their order of arrival for return to the sending stations. Directly above such chute, belt or trough, the outgoing terminals of the carrier tracks are banked in suitably spaced relation and within convenient reach of the operator's stations. With the above described arrangement it is possible for a single operator to serve a large number of outlying stations in proper sequence and without moving from her place, the arrangement permitting the number of operators to be varied in direct ratio to the fluctuations of the business. Moreover, by the employment of two or more readily distinguishable kinds of carrier, as for example, carriers of contrasting color, cashiers and charge account authorizers may use the same or opposite sides of the same desk, each set of operators removing the proper type of carrier from the belt, chute or trough and depositing such carrier, after completing the necessary transaction, in the dispatch end of the proper outgoing track. It is evident, however, that by the arrangement described, any operator is enabled, if necessary, to serve the outgoing stations both as to cash and credit transactions without moving from her place.

Apparatus of the genus illustrated by the mentioned species is simple, inexpensive, and easy to keep in repair, and capable of extension to keep pace with the growth of the system. While the dispatch terminals of the outgoing dispatch lines are shown as so arranged as to be operated by the receiving operators, the dispatch terminals may, if desired, be arranged otherwise, as in a bank removed at some distance from the operator's station, and that carriers, after the desired manipulation by the receiving operators, may be conveyed to such point by any convenient means, such as in the said Whittier Patent No. 1,365,428, for return to the sending stations by a specially authorized person or persons.

In the accompanying drawings, there is shown by way of example one embodiment of means suitable for carrying the above objects into effect and in such drawings,—

Fig. 1 is a longitudinal central vertical section through a typical central-station apparatus constructed in accordance with the present invention;

Fig. 2 is a fragmentary transverse vertical cross section on a line such as A—B of Fig. 1;

Fig. 3 is a similar cross section on a line such as C—D of Fig. 1;

Fig. 4 is a perspective view, to smaller scale, of the device of Fig. 1, certain parts being omitted;

Fig. 5 is a fragmentary detail plan view of the device of Fig. 1, parts being omitted for clearness in illustration;

Fig. 6 is a fragmentary elevation of one

end of apparatus for the same uses as that of Fig. 1, illustrating a modification;

Fig. 7 is a longitudinal section illustrating a further modification;

Fig. 8 is a diagrammatic plan view, partly broken away, illustrating a central station of the type herein disclosed and showing a preferred arrangement of the operators' stations when both cashiers and credit account

authorizers are employed;

Fig. 9 is a similar diagrammatic view showing the arrangement when a single operator is depended upon for performing the work both of a cashier and a credit authorizer; and

Fig. 10 is a front elevation, partly broken away, of a central station desk of further modified construction.

The apparatus as herein illustrated comprises an elongate table or desk 1 which is substantially symmetrical with respect to its longitudinal axis. At a selected portion of such desk, and preferably spaced from the left-hand end thereof as indicated in Fig. 8, 25 operators' stations, as at X, Y, are located at either side thereof, the cashiers occupying stations X, and the charge account authorizers the stations Y. Extending centrally of this desk or table is a slot 3 of substantially 30 the width of the usual carrier and having a bottom wall 4 (Fig. 2), such slot defining a guideway for the passage of carriers longitudinally of the desk. At that portion of the desk located opposite the operators' stations, the desk is provided with depressions 5, 6, having the bottom walls, 7, 8 and the inner side walls 9, 10, the latter walls defining the edges of the guide slot 3 at this portion of the desk. The depressions 5, 6 35 serve for the reception of the cashiers' tills and also to receive the contents of the carriers as the latter are emptied by the operators. If desired, the right-hand portion of the guide slot 3 as viewed in Fig. 1, may be somewhat wider than the remainder of the slot, such widened part being indicated at

While this arrangement may be desirable under certain circumstances, it will in many cases be preferred to continue the guide slot of uniform width throughout the entire length of the desk.

Above the guide slot, at that portion of the desk located between the operators' stations, an elevated table 12, Figs. 1 and 3, mounted upon suitable supports 13, 14 is provided. At the left-hand end of the desk, see Figs. 1 and 2, a guiding and supporting device is arranged, this device comprising the end wall 15 and the spaced parallel side walls 16, 17. The side walls 16, 17 are spaced apart a distance substantially equal to the width of the slot 3 and serve to continue the sides of the latter upwardly to a height such as effectually to prevent the lateral escape of carriers from the slot as

they are deposited therein. Upon the upper edges of the members 16, 17 a series of brackets 18 are secured. These brackets serve as supports for the terminal sections of corresponding guide rail devices as 19, 70 such guide rail devices leading from various sending stations located at suitable points in the store or other establishment where the apparatus is installed.

Associated with each of the tracks 19 is a 75 cable designated 20, 20^a and 20^b, respectively. These cables pass downwardly through openings in the top of the desk and about guide pulleys 21, 21^a, 21^b respectively. The cables then pass about drive pulleys 22, 22^a, 80 22^b and thence upwardly about guide pulleys 23, Fig. 2, and about other pulleys, not shown, to the dispatch terminals hereinafter described. The lower ends of the several rail devices 19 are diverted laterally as indicated at 24 (Fig. 2) the ends 25 of the rails extending downwardly between the side walls 16, 17 of the guiding and supporting device previously described. Preferably the ends 25 of the rails are somewhat curved, as 85 indicated in Fig. 1, whereby carriers delivered from the ends of such rails are deposited properly and in orderly fashion upon the floor of the guide slot 3 after being released from the cable by usual cam 24^a. 90

If desired, each rail terminal may be provided with a buffer device 26 for absorbing a portion of the shock of the carrier as the latter arrives near the end of the railway. This buffer device may comprise a lever 100 pivoted at a point such as 27, and having a suitable piston movable in a cylinder 28, the piston and cylinder operating as a dash pot to absorb the shock of arrival of the carrier. This buffer device operates to slow 105 down the carriers but does not interfere with their free discharge from the lower ends of the rails.

Extending longitudinally of the slot 3 is 110 an endless belt 29 forming a movable floor for such slot. This belt passes around the drive pulley 30 and about the guide pulley 31, such pulleys being mounted upon shafts 32, 33, respectively journaled in the frame of the desk. For tensioning this belt, a 115 weighted roll 34 may be provided, this roll resting upon the lower run of the belt and being supported by lever arms 35 carried by a shaft 36 slidably mounted in the frame of the desk. The pulley 30 may be driven by a belt 37 passing about a pulley 38 fixed upon a shaft 39, such shaft being journaled in the supporting members 2 of the desk, and also having mounted thereon the several 120 drive pulleys 22, 22^a, 22^b, for the cables 125 previously referred to.

The belt 29 as herein shown terminates at the point 40 intermediate the length of the desk, although under some circumstances it may be desired to continue such belt through- 130

out the entire length of the slot 3. The widened portion 11 of the slot 3, see Figs. 1 and 3, is provided with a smooth bottom wall 41 upon which carriers 42 of the usual elongate form employed in cable systems may be deposited by the belt 29.

Upon the top of the elevated table 12 are arranged a series of supports 43, such supports having mounted therein guide pulleys such as 44, 44^a, 44^b, about which extend cables 45, 45^a, 45^b respectively. These cables are continuations of the cables 20, 20^a, 20^b, respectively, and are led from the delivery devices over suitable pulleys (not shown), to the pulleys 44, 44^a, 44^b. These cables cooperate with the dispatch ends 46, 46^a, 46^b, respectively, of a series of railways corresponding to the railway 19 and which extend to the several sending stations. The dispatch ends of the several rails may be constructed in the usual manner and may be lettered or numbered, as at 47, Fig. 3 to indicate the station with which they communicate.

By assembling the delivery ends of all of the several rails at the end portion of the desk, it is made possible to bank both the receiving and the dispatch ends of such rails in close proximity to each other as indicated in Fig. 1, and this places the dispatch ends 46, etc., where they are readily accessible to operators located at either side of the desk. By reason of this compact arrangement it is also possible for a single operator to reach a large number of such dispatch terminals without removing from her position, it being understood that the three terminals illustrated in Fig. 1 designate plurality without specific number, and are typically illustrative of arrangements wherein a much larger number of terminals may be banked in a single group as indicated in Fig. 8, for instance, or in spaced groups, as circumstances may demand.

In the device shown in Fig. 6 the desk is indicated at 50, such desk being supported upon the members 51 and having the elevated table 52 at a point opposite the operators' stations. This table serves to support the dispatch terminals 53, 53^a, 53^b respectively of a series of railways while a supporting and guiding device comprising the spaced side members 55, 56, serve to support the delivery ends 57, 57^a, 57^b of a corresponding series of railways. This supporting and guiding device is provided with an inclined bottom wall 58, thus forming a chute into which the carriers are delivered from the several rail terminals. Such carriers slide down along this bottom wall 58 and into the guide slot 54 which extends longitudinally of the table top. In this device the conveyor belt is omitted, the incline of the guiding chute being depended upon for imparting sufficient momentum to

the carriers to cause them to pass the desired distance along the guide slot.

In Fig. 7 the desk is indicated at 60, such desk being provided with a longitudinal slot 61 and with the elevated table 62 serving to support the dispatch rail terminals 63, 63^a, 63^b, etc. The bottom wall of the slot 61 is provided by an endless belt 64 trained about the driving pulley 65 and the guide pulley 66, such belt being tensioned by the weighted roller 67. Beyond the termination of the belt 64, the bottom of the slot 61 is provided by the stationary member 68 upon which the carriers may be delivered by the belt. The delivery ends of the several railways are indicated at 69^a, 69^b, respectively, such ends serving to deliver carriers into an inclined chute having the bottom wall 70 from which the carriers slide onto the belt.

In Fig. 10 the desk 1^a is illustrated as provided with inclined guide chutes 100, 101 at either end thereof, such chutes having associated therewith the banks of delivery terminals 102, 103 respectively, these terminals herein being indicated as the ends of guide rails of a cable carrier system, it being understood, however, that other types of carrier guide might be substituted therefor if desired. The carriers delivered upon the chutes 100, 101 respectively are received upon the upper runs of endless belt conveyors 104, 105 arranged in an elongate guide slot corresponding to the guide slot 3 of the previously described devices, and are thereby delivered upon the stationary floor 106 disposed opposite the operators' stations. Above this stationary floor 106 is arranged the supporting table 107 upon which are secured the lower ends of the dispatch terminals 108. With this arrangement a relatively large number of outlying stations may be cared for by one or more operators seated at the central part of the desk, thus providing a very compact type of central station such as is particularly adapted for use in small establishments where but little space is available for the purpose. While as herein illustrated the belt conveyors 104, 105 are employed, it is contemplated that when the desk is of relatively small dimensions such conveyors may be omitted, the inclination of the chutes being sufficient to cause the carriers to move to the central part of the desk.

In the operation of the device of Figs. 1, 2 and 3, carriers arriving along the guide rails 19 are diverted from their normal path and out of engagement with the driving cable at the point 24, and after being slowed down by contact with the buffer members 26, the carriers are dropped freely from the ends 25 of the rails. By reason of the curvature of the rail ends the carriers are deposited in an orderly manner by which they are moved longitudinally of the guide slot 3, and if not previously removed by the opera-

tor, are finally pushed in succession, onto the stationary floor 11 of the guide slot. As the guide slot 3 is of a width such as to prevent any substantial turning of the elongate carriers during their movement longitudinally of the desk, the orientation of the carriers as they arrive opposite the operators' stations is substantially identical. The operator is thus enabled to grasp the carrier with a minimum of voluntary effort, and in such a manner as to permit opening of the same with the utmost dispatch. It is also clear that by the arrangement described carriers are presented to the operators in the order of their arrival so that the transaction of making change or the like and the return of the carriers may be properly performed in accordance with their sequence in arriving, the entire series of unopened carriers being at all times visible. It is also clear that as the dispatch terminals are located within easy reach of the operators' stations it is possible for the operator to return carriers to their sending points with the least possible delay. In the several figures of the drawing, one end only of the desk is illustrated, it being evident that the desk may be made as long as desired, and that additional banks of delivery and dispatch terminals may be added if necessary. It is also contemplated that banks of delivery terminals may be so disposed as to direct their carriers toward a common bank of dispatch terminals.

In order to permit cash and credit carriers to be distinguished it is proposed to mark such carriers with contrasting colors, or to provide them with other means such as to permit the credit authorizers who if desired may be seated at the stations Y upon one side of the desk, to select credit carriers from the stream of carriers arriving, without necessitating the mechanical separation of such carriers from the cash carriers which are equally accessible to the cashiers seated at the stations X the opposite side of the desk. It is also clear that if the volume of business becomes so small that a single person can transact both the cash and credit operations, the carriers are always so located in the guide slot as to be accessible to a single operator seated as at Z, Fig. 9, and at either side of the desk as may be most convenient. With this arrangement it is extremely easy to shift the operators about in accordance with the demands of the business, and to determine the number of operators employed at any time in direct ratio to the number of transactions performed without necessitating any elaborate mechanical means for distributing the incoming carriers to the various operators while at the same time the care of supervision of the employees is greatly reduced.

The devices illustrated in Figs. 6 and 7

operate in substantially the same manner as that described with respect to Fig. 1.

The device shown in Fig. 10 operates in substantially the same manner as those shown in the preceding figures, the only substantial difference being that carriers approach the center of the desk from opposite directions. The operators may be located at this desk substantially as indicated in Figs. 8 or 9 and may care for the incoming carriers and for their return to the sending stations in the same manner as previously described.

What we claim is:

1. A central station for a cable carrier dispatch system having therein a plurality of downwardly directed railway delivery terminals, common means for receiving all carriers delivered from the several terminals, and means for causing carriers deposited upon said receiving means to move successively in a given path lying between operators' stations and within convenient reach therefrom.

2. A central station apparatus comprising in combination a bank of delivery terminals from which carriers of a plurality of distinct classes may be discharged, means for receiving all of such carriers and for moving them past the station of an operator, and a bank of carrier dispatch terminals within convenient reach from said operator's station.

3. A central station apparatus for cable carrier dispatch systems comprising a plurality of carrier delivery terminals from which carriers of a plurality of distinct classes may be discharged, and means for supporting the carriers and causing all carriers delivered from all said terminals to move in a common path extending longitudinally of the supporting means, and operators' stations disposed at the opposite sides of the supporting means and at substantially equal distances from said path.

4. A central station for carrier systems providing stations for oppositely facing operators and comprising a plurality of carrier delivery terminals, and means for causing carriers delivered from all of said terminals to move toward a point at which they are equally accessible while in transit to operators at either of said stations.

5. In combination in a carrier dispatch system of that type wherein the carriers are moved along a track by an endless cable, a central station comprising a bank of delivery track sections having their terminals in substantial alignment, said track sections being so constructed and arranged as to permit carriers to drop freely therefrom, and a guideway for receiving carriers from the several terminals.

6. A central station apparatus comprising a series of pairs of terminal rail sections for

guiding carriers for delivery at said station, said rail sections each being curved adjacent to its extremity, and common means for receiving all carriers delivered by the respective pairs of rail sections and moving them in a single and accessible stream past an operator's station.

7. A central station for carrier dispatch systems comprising a desk providing operators' stations at either side thereof, a series of carrier delivery terminals adjacent to one end of said desk, a guideway for carriers extending longitudinally of said desk and centrally of the width thereof, and means for causing all carriers delivered by the several terminals to move in orderly succession along said guideway, and past the operators' stations.

8. A central station apparatus comprising a carrier delivery terminal, an elongate guideway for carriers delivered from said terminal, said guideway having a longitudinally movable floor, a trough in continuation of said guideway and having a stationary floor extending substantially in the plane of the movable floor, and means for imparting movement to said movable floor whereby to cause carriers to move toward said trough.

9. A central station apparatus comprising a delivery terminal having its extremity curved in a vertical plane, and a chute having relatively high side walls and an inclined bottom, the curved portion of said terminal depending between the walls of said chute.

10. A central station apparatus comprising a vertical carrier delivery terminal having a curved extremity, an inclined chute having side walls between which said curved extremity depends, a belt conveyor aligned with said chute and constructed and arranged to receive carriers therefrom, and a trough aligned with said belt conveyor for retaining carriers delivered by said belt.

11. A central station apparatus comprising a carrier delivery terminal, an inclined open chute having relatively high side walls between which said terminal depends, and a belt conveyor arranged at the delivery end of the chute for conveying carriers away therefrom.

12. In combination in a carrier dispatch system of that type wherein the carriers are moved along a track by an endless cable, a central station comprising a vertically disposed track section having an associated run of cable extending parallel therewith, a guideway for carriers disposed to one side of said track section, and a terminal track section forming a continuation of said vertical section but offset therefrom and terminating within said guideway for delivering carriers thereto.

13. A central station for carrier dispatch

systems of the type employing an endless cable for moving the carrier, said station comprising a bank of delivery terminals, a bank of dispatch terminals spaced therefrom, conveyor means for causing carriers delivered from said first named terminals to move toward the dispatch terminals, and common means for actuating the endless cable and for simultaneously driving said conveyor means.

14. A central station for carrier dispatch systems comprising a delivery terminal, means for causing a carrier delivered from such terminal to move in a substantially rectilinear path, operators' stations at opposite sides of said path, and within convenient reach thereof, and means for maintaining unchanged the orientation of such carrier throughout its movement along a portion at least of said path.

15. A central station for carrier dispatch systems comprising a delivery terminal, a guide slot for carriers delivered from said terminal, said guide slot being constructed and arranged to prevent turning of a carrier therein, and means for causing a carrier deposited in said guide slot to move lengthwise of the same.

16. A central station for carrier dispatch systems wherein carriers of elongate form are employed comprising an open topped guideway having fixed side walls spaced apart a distance substantially equal to the width of the carriers, a carrier delivery terminal constructed and arranged to deliver carriers into the space between said walls, and means for moving such carriers along said guideway.

17. A central station for carrier dispatch systems providing a plurality of operators' stations and a series of carrier delivery terminals, a substantially horizontal guideway extending longitudinally of said stations, said guideway being of a width substantially equal to that of the carriers employed, a belt conveyor arranged within said guideway and constituting the floor thereof for a portion of its length, and means for actuating said belt whereby to cause carriers delivered into said guideway from said terminals to travel longitudinally of the guideway.

18. In combination in a carrier dispatch system of that type wherein the carriers are moved along a track by an endless cable, a central station comprising a plurality of operators' stations, and a bank of dispatch track terminals common to and within reach of each of said stations.

19. A central station comprising a plurality of receiving terminal rail sections of a cable carrier system, an operator's station spaced therefrom, common means for conveying all carriers delivered by said ter-

- 5 minal sections to the operator's station, and a bank of dispatch rail sections for cable lines returning to the points of origin of the carriers delivered by the respective receiving terminal sections, said bank of dispatch sections being arranged adjacent to the operator's station.
- 6 20. A central station comprising a desk having adjacent to one end thereof a bank 45 of carrier receiving terminals, an operator's station at the side of the desk, an endless, movable belt for receiving carriers delivered by said terminals and for conveying carriers to said operator's station, and a bank 50 of dispatch terminals arranged in a plane above that of the belt and with inconvenient distance of the operator's station.
- 7 21. A central station comprising a desk having operators' stations upon either side 55 thereof, a guideway for carriers extending longitudinally and centrally of the desk, a table spaced above said guideway at the region of the operators' stations, a bank of dispatch terminals upon said table, a bank 60 of delivery terminals adjacent to one end of said guideway, and means for causing carriers delivered by said terminals to move in orderly succession along said guideway and within reach of the operators' stations.
- 8 22. A central station comprising an elongate guideway, an operator's station upon either side thereof, a plurality of carrier dispatch terminals arranged within reach of each of said stations, and means for causing carriers to move in orderly succession 65 along said guideway.
- 9 23. A central station comprising an elongate guideway, an operator's station at either side thereof, a plurality of carrier dispatch terminals arranged above said guideway and intermediate the ends thereof, and means for causing carriers to move 70
- 10 toward the central portion of said guideway from either end thereof.
- 11 24. A central station comprising an elongate guideway, an operator's station substantially midway of the length thereof and an inclined chute at either end of said guideway for delivering carriers thereto from opposite directions. 75
- 12 25. A central station comprising an elongate guideway for carriers, operators' stations substantially midway of the length thereof, a bank of carrier delivery terminals within reach of said stations, and chutes for delivering carriers into opposite 80 ends of said guideway.
- 13 26. A central station for cash carrier systems comprising an elongate guideway for carriers, operators' stations upon either side 85 of said guideway and intermediate the ends thereof, a bank of carrier delivery terminals disposed above said guideway and within reach of said stations, and a pair of chutes inclined downwardly in opposite directions 90 and constructed and arranged to deliver carriers into the opposite ends of said guideways.
- 14 27. A central station comprising an elongate desk having operators' stations upon either side thereof, a table extending longitudinally of the desk in the region of the operator's stations and elevated above the central part thereof, a plurality of carrier dispatch terminals mounted upon said table, 95 and means for delivering carriers at the central portion of the desk and beneath said table for convenient access to operators upon either side of the table.

Signed by us at Boston, Massachusetts, 80
this second day of August, 1922.

FREDERICK G. WHITTIER.
HAROLD S. THAYER.

5 minal sections to the operator's station, and a bank of dispatch rail sections for cable lines returning to the points of origin of the carriers delivered by the respective receiving terminal sections, said bank of dispatch sections being arranged adjacent to the operator's station.

20. A central station comprising a desk having adjacent to one end thereof a bank 10 of carrier receiving terminals, an operator's station at the side of the desk, an endless, movable belt for receiving carriers delivered by said terminals and for conveying carriers to said operator's station, and a bank 15 of dispatch terminals arranged in a plane above that of the belt and with inconvenient distance of the operator's station.

21. A central station comprising a desk having operators' stations upon either side 20 thereof, a guideway for carriers extending longitudinally and centrally of the desk, a table spaced above said guideway at the region of the operators' stations, a bank of dispatch terminals upon said table, a bank 25 of delivery terminals adjacent to one end of said guideway, and means for causing carriers delivered by said terminals to move in orderly succession along said guideway and within reach of the operators' stations.

30. 22. A central station comprising an elongate guideway, an operator's station upon either side thereof, a plurality of carrier dispatch terminals arranged within reach of each of said stations, and means for causing 35 carriers to move in orderly succession along said guideway.

23. A central station comprising an elongate guideway, an operator's station at either side thereof, a plurality of carrier 40 dispatch terminals arranged above said guideway and intermediate the ends thereof, and means for causing carriers to move

toward the central portion of said guideway from either end thereof.

24. A central station comprising an elongate guideway, an operator's station substantially midway of the length thereof and an inclined chute at either end of said guideway for delivering carriers thereto from opposite directions. 45

25. A central station comprising an elongate guideway for carriers, operators' stations substantially midway of the length thereof, a bank of carrier delivery terminals within reach of said stations, and 50 chutes for delivering carriers into opposite ends of said guideway.

26. A central station for cash carrier systems comprising an elongate guideway for carriers, operators' stations upon either side 55 of said guideway and intermediate the ends thereof, a bank of carrier delivery terminals disposed above said guideway and within reach of said stations, and a pair of chutes inclined downwardly in opposite directions 60 and constructed and arranged to deliver carriers into the opposite ends of said guideways.

27. A central station comprising an elongate desk having operators' stations upon either side thereof, a table extending longitudinally of the desk in the region of the operator's stations and elevated above the central part thereof, a plurality of carrier dispatch terminals mounted upon said table, 75 and means for delivering carriers at the central portion of the desk and beneath said table for convenient access to operators upon either side of the table.

Signed by us at Boston, Massachusetts, 80 this second day of August, 1922.

FREDERICK G. WHITTIER.
HAROLD S. THAYER.

Certificate of Correction.

It is hereby certified that in Letters Patent No. 1,537,569, granted May 12, 1925, upon the application of Frederick G. Whittier, of Ipswich, Massachusetts, and Harold S. Thayer, of Tenafly, New Jersey, for an improvement in "Central Stations for Carrier-Dispatch Systems," an error appears in the printed specification requiring correction as follows: Page 7, line 16, claim 20, for the words "with inconvenient" read *within convenient*; and that the said Letters Patent should be read with this correction therein that the same may conform to the record of the case in the Patent Office.

Signed and sealed this 28th day of July, A. D. 1925.

[SEAL.]

KARL FENNING,
Acting Commissioner of Patents.
